T. A. POMIJE,
J. W. EMMERS.

BY THEIR ATTORNEY.

James F. Williamson

UNITED STATES PATENT OFFICE.

THE OFIL A. POMIJE AND JOHN W. EMMERS, OF LE SUEUR CENTER, MINNESOTA.

SOCKET WRENCH.

Application filed March 19, 1923. Serial No. 625,961.

This invention relates to a socket member such as the well known socket wrench or key and particularly to a cleaning and ejecting device therefor. When such socket wrenches are used to remove a nut, the nut often sticks in the socket owing to the fact that said nut is often burred or damaged and trouble and inconvenience are often experienced in removing said nut, which operation usually takes considerable time. Such socket wrenches also tend to accumulate dirt, grease, etc., in the socket, which often becomes hard and interferes with the quick application and use of the wrench. It is an object of this invention therefore, to provide a socket wrench having simple and efficient means for cleaning the same and ejecting a nut therefrom.

It is a further object of the invention to provide such a cleaning means comprising a plurality of spaced prongs movable longitudinally in the socket and preferably fitting close against the sides of the socket walls. It is a further object of the invention to provide a socket wrench having a shank extending from one end on which slides a sleeve carrying the prongs which are movable in the socket, said shank also preferably being provided with means limiting the movement of said sleeve.

These and other objects and advantages of the invention will more fully appear from the following description made in connection with the accompanying drawings, in which like reference characters refer to the same parts throughout the different views, and in which,

Fig. 1 is a view in elevation of the device, a small portion thereof being shown in section;

Fig. 2 is a horizontal section taken on line 2—2 of Fig. 1 as indicated by the arrows;

Fig. 3 is a vertical section taken on line 3—3 of Fig. 1 as indicated by the arrows;

Fig. 4 is a view in front elevation of one of the parts of the device;

Fig. 5 is a horizontal section taken on line 5—5 of Fig. 4 as indicated by the arrows;

Fig. 6 is a view in front elevation of a modified form of one of the parts;

Fig. 7 is a horizontal section taken on

line 7—7 of Fig. 6 as indicated by the arrows; and

Fig. 8 is a vertical section taken on the line 8—8 of Fig. 3.

Referring to the drawings, the device comprises a member or head 1 illustrated as of substantially cylindrical form having therein an angular socket 2 opening at one end thereof. The member 1 is substantially closed at its other end and has projecting therefrom a shank 3 illustrated as of cylindrical form, which shank is of smaller diameter than the socket 2. A shoulder is thus formed between the member 3 and one end of the head 1 and said head has a plurality of openings extending through this shoulder into the socket 2. The shank 3 has a sleeve 4 fitting and slidable thereon, from one end of which project a plurality of narrow prongs 5. These prongs 5 project into the openings in said shoulder and thus extend into the socket 2 and in the embodiment of the invention illustrated, said prongs are shown as of substantially triangular shape in cross section and having their outer sides fitting the angles formed by said socket walls and disposed closely adjacent said walls. The movement of the sleeve 4 away from the head 1 is limited by any suitable means secured to the shank 1, such as the illustrated screw 6 threaded into said shank. The shank is provided at its end remote from the head 1 with a squared or angular portion 7 affording means for turning said head 1 by the application of a suitable wrench.

In operation, the device will be placed in position with the socket 2 fitting over a nut and the wrench turned to remove the nut. After the nut is removed, the same can be quickly ejected by sliding the sleeve 4 longitudinally of the shank 3, it being understood, of course, that said sleeve and prongs 5 are withdrawn during the removal of the nut. The sleeve 4 and prongs 5 can also be reciprocated to clean out and eject any dirt, grease, etc., which has lodged in the socket 2.

If desired, more than two of the prongs 5 can be provided and in the modification shown in Figs. 6 and 7, the sleeve 8 which is similar to and a counterpart of the sleeve 4 is provided with six prongs 9 similar to the prongs 5, which prongs 9 are shaped to fit in

the angles of the socket. With such a device, all of the dirt which might collect in the socket and the angles thereof will be quickly ejected therefrom and a nut can also be quickly and easily ejected from the socket.

From the above description, it is seen that applicant has provided an extremely simple and efficient means for cleaning a socket wrench and ejecting a nut therefrom. By 10 having the prongs oppositely arranged, the pressure is evenly distributed on the nut so that there is no tendency for the same to bind in the socket as would be the case if the nut were engaged only at one edge. The 15 sleeve 4 slides easily on the shank 3 and it will be noted that the dimensions of the wrench are not increased by the cleaning and ejecting means, so that the wrench can be used in the small spaces. The cleaning and 20 ejecting means thus do not interfere in any way with the use of the wrench. It will be noted that more than one nut can be removed before the nuts are ejected from the socket, the ejecting means insuring that said nuts 25 will not become fastened in the socket. Time is thus saved in removing a large number of nuts. If the head 1 should be twisted off of the shank 3, the sleeve 4 and prongs 7 can readily be reset or applied to a new 30 shank. The device is easily made and assembled and can be produced at small expense.

It will, of course, be understood that various changes may be made in the form, details and arrangement and proportions of the parts without departing from the scope of applicant's invention, which generally stated consists in the manner shown and described and set forth in the appended claims.

40 What is claimed is:

1. A socket wrench comprising a head having an angular socket therein opening at one end thereof, a shank extending longitudinally from the other end of said head 45 and of smaller diameter than the diameter of said socket thus forming a shoulder

against said head, said head having a plurality of openings extending through said shoulder longitudinally of said head, a sleeve 50 slidable on said shank and carrying a plurality of prongs slidable through said openings to engage a nut held in said socket for ejection.

2. A socket wrench comprising a head having an angular socket therein opening at 55 one end thereof, a shank extending longitudinally from the other end of said head and of smaller diameter than the diameter of said socket thus forming a shoulder against said head, said head having a plurality of 60 openings extending through said shoulder longitudinally of said head, a sleeve slidable on said shank and carrying a plurality of prongs slidable through said openings to engage for ejection a nut held in said socket, 65 said prongs being arranged in pairs at diametrically opposite sides of said socket to exert equal pressure at opposite sides of the nut.

3. A socket wrench comprising a head having an angular socket therein opening at one 70 end thereof, a shank integral with and extending longitudinally from the other end of said head and of smaller diameter than the diameter of said socket, thus forming a 75 shoulder against said head, said head having a plurality of openings extending through said shoulder longitudinally of said head, a sleeve 80 slidable on said shank and carrying a plurality of narrow prongs substantially triangular in cross section 85 slidable through said openings and fitting in the angles formed by the walls of said socket, said prongs being arranged in pairs at opposite sides of said socket, and means on said shank limiting the outward movement of said sleeve and prongs, said prongs being adapted to clean the socket and eject a nut therefrom.

In testimony whereof we affix our signatures.

THEOFIL A. POMIJE.
JOHN W. EMMERS.
